Primary Examiner — Dana K Weiland*Assistant Examiner* — Emily Anna Saunders(74) *Attorney, Agent, or Firm* — True Shepherd LLC;
Andrew C. Cheng(57) **CLAIM**

The ornamental design for a toy bubble mower, as shown and described.

DESCRIPTION

FIG. 1 is a perspective view of a toy bubble mower showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof; and,

FIG. 7 is a top plan view thereof.

The broken lines depict portions of the toy bubble mower and form no part of the claimed design.
